(57) **CLAIM**

The ornamental design for a pet-safe tethering and escape tree, as shown and described.

DESCRIPTION

FIG. 1 is a perspective top, front and left side view of a pet-safe tethering and escape tree, showing our new design; FIG. 2 is a left side view thereof, the right side view being a mirror image;

FIG. 3 is a front view thereof;

FIG. 4 is a rear view thereof; and,

FIG. 5 is a top view thereof.
